ATTORNEYS

UNITED STATES PATENT OFFICE.

HENRY RIDGEWAY HART, OF MONTCLAIR, NEW JERSEY.

NONSINKABLE COAT.

Application filed May 29, 1922. Serial No. 564,342.

To all whom it may concern:

- Be it known that I, HENRY RIDGEWAY HART, a citizen of the United States, residing in Montclair, in the State of New Jersey, 5 have invented certain new and useful Improvements in Nonsinkable Coats, of which the following is a specification, reference being had to the accompanying drawings, forming a part hereof.
- 10 This invention relates to a coat which is warm and comfortable and yet is of such construction as to be nonsinkable and actually afford sufficient buoyancy to sustain the body of the wearer in case he is accidentally thrown into the water. Such a coat has especial usefulness for aviators. The principal object of the invention is to provide a coat which shall present an external appearance of conventional and 15 slightly form and be thoroughly comfortable in conformation and yet have incorporated directly therein material which will afford sufficient buoyancy to keep the wearer afloat. Another object of the invention is to provide 20 buoyant material in such a coat which shall be of such character and so distributed as to place the center of buoyancy of the wearer above the center of gravity so as to maintain him in upright position, or substantially so, when afloat. A third object of the 25 invention is to provide in such a non-sinkable coat means which shall hold the same in desired relation to the body of the wearer, when afloat, and prevent its disarrangement 30 with respect thereto so that the center of buoyancy will always be maintained in substantially its predetermined relation to the body. In accordance with the last named 35 object of the invention a strap arrangement is provided which will prevent the coat from riding up on the body and yet will be of unobjectionable form and appearance and partially concealed when the coat is in ordinary use.
- 40 The objects enumerated above will appear more clearly with reference to the description of the preferred embodiment of the invention which is illustrated in the accompanying drawings. In the drawings:
- 45 Figure 1 is a view in elevation of the improved coat, one of the flaps being turned back to show the relation of the retaining strap to the crotch of the wearer.
- 50 Figure 2 is a view in vertical transverse section through the coat illustrated in Fig-

ure 1 and showing the manner in which the buoyant material is incorporated.

The coat *a* is made of any suitable warm and water-proof material such as water-proofed gabardine. An inner lining *a'* of similar material is provided. Incorporated directly between the outer cloth *a* and the inner lining *a'* is a stuffing *b* of quilted ilan-silk or kapok, which adds warmth to the coat and is of pliable buoyant material. 60 This kapok possesses properties which lends itself admirably to the use described in that it is readily tailored and conforms in a desirable way to the lines of the body and insures the provisions of a thoroughly comfortable and well fitting garment. In accordance with the invention the buoyant material is so disposed with respect to the coat and is of such bulk at different sections thereof as to place the center of buoyancy, 70 indicated at *X* in Figure 1 well above the center of gravity of the wearer, thereby maintaining the body in substantially upright position when afloat. To this end, it will be observed from Figure 2 that the 75 kapok *b* is not extended to a point far below the waist of the wearer and that it is placed in substantially greater bulk above the waist, in the region of the chest, than it is lower down. In this way, the desired disposition of the center of buoyancy is se- 80 cured.

It will be understood that a non-sinkable coat to be effective must be held against riding up on the body or disarrangement with 90 respect thereto when the body is afloat. Accordingly, the improved coat is provided with a retaining strap which prevents such disarrangement in a very satisfactory manner and is itself of unobjectionable form 95 and appearance. A belt *c* encircles the waist and is held in predetermined relation thereto by means of loops *d*. This belt, while of pleasing appearance in a garment of this kind, performs an important mechanical 100 function in the improved coat. From Figure 2 it appears clearly that a retaining strap *e* is buttoned as at *f* on to the coat in the center of the back and passes downward over the belt *c*. It is passed through the 105 crotch of the wearer and up under the front of the coat as shown in Figure 1 and buttoned on to one of the retaining buttons *a'* of the coat itself. In ordinary use, it will be evident that this strap *e* might be re- 110

moved entirely from the coat or, if not removed, appears only to a very slight degree at the back of the coat and does not show at all in front. When the wearer is afloat the 5 strap *e* prevents the coat from riding up on the body and holds it against disarrangement so that the center of buoyancy is not disturbed. Some of the pressure imposed on the strap at this time is transmitted directly by it to the encircling belt *c* which, 10 being rather tight on the body transmits some of these strains to the body over a great length.

From the description given it will be evident that the improved coat not only serves 15 ordinarily as a warm and comfortable garment for general sport wear and for aviation but, being non-sinkable, affords an additional factor of safety against drowning 20 in case the wearer gets overboard. The

features particularly described herein are such as have been found in practice to satisfy the requirements of the art.

What I claim is:

A non-sinkable coat of the character described, comprising buoyant material incorporated with the upper part of the coat so that the center of buoyancy of the wearer is above his center of gravity, and a strap buttoned to the back of the coat, extending 25 downwardly, between the legs of the wearer, and upwardly, underneath the lower front portion of the coat and buttoned at its end to the coat, whereby the strap is substantially invisible from the front and a belt encircling the waist exteriorly of the coat. 30

This specification signed this 26th day of May A. D. 1922.

HENRY RIDGEWAY HART.
